[57] CLAIM

The ornamental design for a feeder for poultry, as shown and described.

DESCRIPTION

FIG. 1 is a front elevation view of a feeder for poultry showing my new design, it being understood that the broken lines are for illustrative purposes only and form no part of the claimed design;

FIG. 2 is a top plan view thereof;

FIG. 3 is a bottom plan view thereof;

FIG. 4 is a side elevation view thereof.

FIG.1

FIG.2

FIG. 3

FIG. 4
